AIR CONDITIONING SYSTEM

Edward A. Bailey, West Caldwell, N. J., assignor
to General Electric Company, a corporation
of New York

Application March 21, 1936, Serial No. 70,100

19 Claims. (Cl. 257—3)

My invention relates to air conditioning systems and more particularly systems adapted for both automatic heating and cooling in year around service.

5 The principal object of my invention is to provide improved means for controlling a multiple zone system of the above type.

It is also an object of my invention to provide each zone with an individual air conditioner having heat exchange apparatus with variable 10 heat exchange areas and time controlled means for selectively varying these areas.

More specifically, it is an object of my invention to provide each zone with an individual air conditioner having cooling means comprising main and auxiliary heat absorbing surfaces, to selectively supply the main surfaces of each conditioner with refrigerant in response to temperature variations in some space in which such 15 variations are representative of the average space within the respective zones, and to supply refrigerant to said auxiliary surfaces at certain predetermined periods to thereby selectively vary the total effective heat absorbing surface of the cooling 20 means associated with each conditioner.

It has been found desirable to divide large buildings that are to be conditioned into a plurality of zones in order more economically to condition the same and to more readily control the standard of conditions maintained within the 25 various parts of the building. Each zone may consist of a number of rooms or spaces having heat losses and gains that may be considered average and others that are different. The flow of heat exchange medium to the average rooms 30 may be controlled by a thermostat placed at some point that is representative of the average space while the flow to the other rooms may be controlled by individual damper controlling thermostats in those rooms.

In numerous instances it happens that the building is of considerable length and placed in the north and south position, or otherwise, because of its plan of construction, possesses considerable area subject to the effect of the sun's 35 radiation during the major part of the day, especially during those seasons when cooling is most likely to be required. Calculations show that the effect of the sun's radiations is considerable and that the load imposed on the cooling apparatus associated with a particular zone varies over a considerable range each day as the sun's rays strike the zone at different angles or strike more or less of the area defining a particular zone.

It is, therefore, an object of my invention to divide the building into zones, some predominantly affected by the sun in the morning and the others in the afternoon, and to provide each zone with a conditioner comprising main cooling 5 means and an auxiliary cooling means whose capacity may be shifted from one conditioner to the other to compensate for variations in the cooling load resulting from the variable position of the sun.

10 It is a further object of my invention to provide each zone and its associated conditioner with an independent cooling control and to provide time controlled means for shifting the auxiliary cooling means and its associated control from one zone to the other.

15 A still further object of my invention is the provision of control whereby the auxiliary cooling means will be placed into operation when the temperature within a particular zone reaches 20 a predetermined value and the main cooling means later if the temperature reaches a second predetermined and higher value so that the periods of operation of the apparatus will be 25 more nearly equal.

Another object of my invention is the provision of a control for the year around conditioner whereby the same will selectively heat or cool the building without the requirement of manual 30 operations.

35 In the past when a central duct system with branch ducts leading to the various rooms of the building has been used it has been customary to utilize a thermostat positioned within each room to control the flow of conditioned medium to that room. When the operation of the conditioner has been changed from heating to cooling and vice versa, it has been necessary manually to change the connections between the room 40 thermostat and the means for regulating the flow of medium in order to admit the flow of heated medium to the room on a decrease in temperature below a certain value and cooled medium on an increase in temperature above 45 another value. It is an object of my invention to obviate this requirement and to provide an improved automatic thermostat reversing control for regulating the flow of the medium at different temperatures and having a separate thermostatically controlled concatenated reversing means for automatically reversing with respect to temperature the reversing control of the thermostat on the flow regulating means 50 for automatically reversing with respect to tem-

perature the action of the thermostat on the flow regulating means.

It is a further object of my invention to provide an additional thermal responsive means located, similarly to the cooling control at some point the temperature of which is representative of the zone for controlling the heating means associated with each conditioner and the reversal of the room thermostat, so that when the 10 conditioner is effective to heat the conditioning medium the action of the thermostat is reversed.

In conditioning large buildings it is necessary to meet the varying requirements of a large 15 number of tenants. In a system of the type under consideration it is obvious that under certain conditions the flow of air through any particular room is stopped when the damper is operated into a closed position. It is, therefore, a 20 further object of my invention to provide means whereby any space or spaces may be supplied with continuously circulated air.

Specifically, this last mentioned object is accomplished by providing an independent duct 25 leading to a certain room or rooms from a point intermediate the air circulating means and conditioning means of the conditioner and providing mechanically interconnected dampers in the two branch ducts leading to the room and under the 30 control of a single thermostat located within the room. The thermostat is arranged to control the damper actuating means so that the latter will simultaneously open one duct and close the other in response to conditions within 35 the room to maintain a continuous circulation of either conditioned or by-passed air therethrough.

The features of my invention which are believed to be new and novel will be pointed out in the 40 claims appended hereto. For a better understanding of the invention reference is made in the following description to the accompanying drawing, partially diagrammatic, illustrating a system embodying my invention.

45 In the single figure I have illustrated in diagrammatical fashion a building 10 consisting of two zones 11 and 12, the former which, for convenience, may be considered as being the east side of the building and the latter the west side. 50 Zone 11 is accordingly affected to a considerably greater degree by the sun's rays in the morning and zone 12 in the afternoon. Because of limitation of space, I have illustrated but three rooms in each zone, rooms A, B, and C in zone 11 and 55 rooms D, E, and F in zone 12, but it is obvious that any number of rooms may be placed in each zone. Furthermore, it is obvious, as will appear more fully later, that my invention is not limited to systems consisting of two zones only. Any 60 number of zones may be conditioned equally well.

Each zone is supplied with conditioned air from its associated conditioner and a central duct system. Zone 11 is provided with a conditioner 13 from which conditioned air is circulated to 65 the various spaces or rooms within the zone through a central duct 14 and a plurality of branch ducts 15 leading to the respective rooms. The air is returned through branch ducts 16 to a central return duct 17 leading back to the 70 conditioner 13. In similar manner, zone 12 is provided with a conditioner 18, a central air duct 19, and branch ducts 20 leading to the respective rooms within that zone. The air is likewise returned to conditioner 18 through branch 75 ducts 21 and central return duct 22.

As stated previously certain rooms having an average heat loss and gain are provided with continual circulation of heat exchange medium and others, subject to unusual conditions, are provided with dampers controlled by thermostats 5 placed in those rooms. Rooms C and F are of the type having average heat gain and loss and are thus illustrated as being supplied with heat exchange medium directly from the central duct and have no dampers controlling the flow thereof 10 to the rooms.

The flow of air to other rooms subject to unusual conditions is controlled by thermostats 25, 26, 27, and 28 in rooms A, B, D, and E, respectively. The thermostats control, in a manner to 15 be more fully described hereinafter, individual means 29, 30, 31, and 32, respectively, adapted to actuate flow regulating means such as dampers 33, 34, 35, and 36, respectively.

Because of the fact that certain tenants require different types of conditioning it often occurs that it is desirable to continuously circulate the conditioning medium through a space subject to unusual conditions. To obtain this result there is provided an independent duct 24 leading to room B from a point intermediate the medium circulating and conditioning means of conditioner 13. Positioned in duct 24 is a damper 37 also operated by damper actuating means 30 under the control of thermostat 26 in room B. Dampers 34 and 37 are so interlinked that when one damper is closed the other is open. By this construction continuous flow of air through room B is provided and it may be seen that such flow will consist of either conditioned air, when damper 34 is open, or unconditioned air, that is, a combination of recirculated and fresh air, when damper 37 is open. The proportions of fresh air and recirculated air are controlled by a plurality of dampers indicated generally by reference numeral 38, positioned, as illustrated, in the central return ducts and in the fresh air ducts 39 and 40 associated with each conditioner.

The conditioner 13 associated with zone 11 consists of air circulating means such as a motor driven fan 41 and means for heating and cooling the air. Means for humidifying the air are usually provided but they are not shown in the figure. The heating means consists of a coil 42 positioned in the path of the air flow and through which flows a suitable heat exchange medium, such as steam, under the control of a two position motor operated valve 43. The cooling means comprises a pair of heat absorbing surfaces consisting of a main evaporator 44 and an auxiliary evaporator 45 for cooling the air as it flows through the conditioner. Heat absorbing surface 44 is supplied with refrigerant or other cooling medium through a conduit 46 under the control of a thermostatic valve 47 to which liquid refrigerant is supplied through conduit 48 from a liquid receiver 49. The latter is connected to a condenser 50 which may be cooled by any desirable means, not shown. The condenser is connected to a compressor 51 adapted to compress vaporized refrigerant conducted thereto from evaporator 44 through a conduit 52. Compressor 51 is driven by any suitable means such as an electric motor 53 which receives power from a suitable source in a manner 60 to be described later.

Conditioner 18 associated with zone 12 is likewise provided with a heating coil 56 which is supplied with steam under the control of a two position motor operated valve 57. The condi- 70

tioner is also provided with main and auxiliary heat absorbing surfaces such as evaporators 58 and 59. Evaporator 58 receives refrigerant through a conduit 60 under the control of a thermostatic valve 61. A conduit 62 connects the latter to a liquid receiver 63 which is in turn connected through a condenser 64 to a compressor 65. The evaporated gaseous refrigerant is led back from evaporator 58 to the compressor through conduit 66. The compressor is driven by any suitable motive means such as an electric motor 67 connected to a suitable source of power.

Auxiliary evaporators 45 and 59 associated with conditioners 13 and 18 respectively are selectively furnished with refrigerant, the former during the forenoon when the sun is in the east and the latter during the afternoon when the sun is in the west from a compressor 68, driven by a suitable electric motor 69, the compressed refrigerant flowing through condenser 70 and liquid receiver 71 to a conduit 72. When it is desired to admit the refrigerant to evaporator 45, an electrically operated valve 73 positioned in conduit 72 permits the refrigerant to flow to the evaporator under the control of a thermostatic valve 74. The evaporated refrigerant is led back to the compressor through conduits 75. When it is desired to render evaporator 59 effective, an electrically operated valve 76 in conduit 72 is actuated to its open position to admit the flow of liquid refrigerant to evaporator 59 under the control of a thermostatic valve 77. The gaseous refrigerant is thereafter led back to the compressor through conduits 75. The operation of valves 73 and 76 is under the control of suitable timing apparatus, to be described hereinafter, permitting but one of these valves to be in its open position at any particular time. The operation of the cooling units driven by motors 53, 67, and 69 is suitably controlled by thermal responsive means positioned in the zones at places having a heat loss and heat gain representative of the average space in the zone.

Before describing the improved control in detail I shall, for purpose of simplification, outline it briefly. The control of the cooling system is independent of the control of the heating system, that is, independent thermal responsive controls are provided for each system. In addition, the operation of each conditioner is controlled by thermal responsive means positioned within the zone with which the conditioner is associated. The thermal responsive means are, in the conditioning system I have illustrated, located at some point the temperature of which is representative of the temperature of the entire zone and, as stated above, rooms C and F are of this nature. In addition, the auxiliary cooling apparatus is provided with a double control, one control being located in one zone and the other in the second. The control is in turn transferred from one zone to the other by suitable time control means that operates simultaneously to shift the control from one zone to another and to close the electrically operated valve in one refrigerant line and open that in the other.

For purpose of simplicity the control of the cooling system will be described first. In room C of zone 11 I have provided a suitable thermal responsive means such as a thermostat 81 comprising a suitable bimetallic thermal responsive element 82 with which is associated a pair of normally stationary contacts. The thermostat is so constructed that the thermal element moves

to the left in response to an increase in temperature and upon engagement with its left hand contact will close an energizing circuit for an associated relay. Engagement by the thermostat of its right hand contact on a temperature change in the opposite direction de-energizes the relay as will be described. The contacts and thermal element are connected by means of conductors 83, 84, and 85 to a relay indicated generally at 86 comprising a suitable transformer 87 and a relay winding 88. The transformer is provided with energy from a suitable source 89 by conductors 90 and 91, the latter being connected to the source through a switch 92. It may be noted that when thermostatic element 82 moves to connect conductors 83 and 84 that relay 88 is energized to establish a holding circuit for itself through switch 93. Simultaneously therewith, switch 94 is closed to energize relay 95 by connecting the latter across supply lines 20 89 through conductors 96, 97, and 98. Energization of relay 95 effects closure of switch 99, which in turn energizes motor 53 by connecting the latter to the supply line through conductors 100.

After the cooling system remains in operation for a sufficient length of time to cool the zone and decrease the ambient surrounding thermostat 81 to a point where thermal responsive element 82 makes contact with its right hand contact then a circuit is closed across conductors 84 and 85. This results in the short circuiting of relay 88 and in actuation of switches 93 and 94 to their open positions, thus de-energizing compressor motor 53 and rendering ineffective 35 the cooling system.

The control of conditioner 18 by a thermostat positioned at a point the temperature of which is representative of the entire zone, that is, in room F, is similar to that just described in connection with zone 11. A thermostat 101 consisting of a thermal responsive element 102 and associated stationary contacts is connected by conductors 103, 104, and 105 to a relay 106 comprising a transformer 107 and a relay winding 108. The transformer primary is connected to supply lines 89 through conductors 109 and 110 and a switch 111 provided with time delay means 112. The purpose of providing switch 111 with a time delay is to obviate certain disadvantages that might be occasioned if both compressor units were started simultaneously. With the arrangement shown, it is obvious that but one unit may be started at any particular moment, thus obviating any sudden large demands on the power supply. Associated with relay winding 108 is a switch 113 adapted to close a holding circuit for the winding when the latter is energized and a switch 114 adapted to close an energizing circuit for relay 115. The energizing circuit for the last mentioned relay is from one side of supply 89 through conductor 116, switch 114, conductor 117, relay 115 and conductor 118 to the other side of the supply. Upon energization of relay 115 its associated switch 119 is actuated into its closed position to close an energizing circuit for compressor motor 67 through conductors 120.

It may be noted that when the thermal element 102 moves to the left into engagement 70 with its left hand contact upon an increase in temperature to close a circuit across conductors 103 and 104, relay winding 108 is energized to cause operation of compressor motor 67. When the temperature within the zone and surround- 75

ing thermostat 101 decreases to a predetermined value then a circuit is formed across conductors 104 and 105 to short circuit relay winding 108 to effect de-energization of compressor motor 67.

5 I shall now discuss briefly the details of the control of the auxiliary cooling apparatus. As stated previously, the apparatus is under the control of time controlled means so that the refrigerant is circulated to either one conditioner 10 or the other during certain predetermined periods and also under the control of thermal responsive means within the zone to which the conditioner supplies conditioned medium. The 10 control is supplied with energy from source 89 through conductors 121 and through time controlled switches 122 and 123 comprising telechron motors 124, permanently connected across the supply line, and mercury type switches 125 and 126. These switches are disclosed only 15 schematically since they are well known to those skilled in the art. Control switch 122 is provided for the purpose of controlling the energization of the apparatus as an entirety. In some systems it is desirable that the system 20 function only during certain periods of the day and switch 122 is so constructed that it will close a circuit only during the desired periods of the day; or it may be constructed in such manner that no cooling will take place on predetermined days. Obviously, the switch may be dispensed with entirely if cooling is desired at all times.

Considering first the operation of switch 122 as it effects the energization of the refrigerating apparatus already described, it will be noted that one pole of the switch is connected to one of the supply lines 89 through conductors 121 and 127. The other pole of the switch is connected by conductor 128 to relay winding 129 which controls 25 the operation of a switch 92 governing the operation of compressor motor 53, and switch 111 governing the operation of compressor motor 67. Conductor 128 is connected by means of conductor 130 to the middle pole of switch 126. 30 Switch 126 is of a type that makes contact between the middle pole and the right hand pole during certain periods and between the middle pole and the left hand pole at other periods. For purpose of illustration it will be assumed 35 that the switch is so co-ordinated with its driving means that the middle and right hand poles are connected during the forenoon and the middle and left hand poles during the afternoon. The right hand pole is connected by means of conductor 131 to the primary winding of a transformer 132 from which leads a common connection 133 to one side of the power line. Thus, when switch 126 is in the position where 40 the middle and right hand poles are connected, transformer 132 is energized and when the switch is in its opposite position, a circuit is formed by conductor 134 through the primary winding of transformer 135.

Associated with transformer 132 is a relay 45 winding 136, the energization of which is controlled through conductors 137, 138, and 139, by a thermal responsive means located in room C. Conductor 137 is connected to the thermal element 140 of thermal responsive means 141 and 50 conductors 138 and 139 are connected to the right and left hand contacts thereof, respectively. It will be seen that when the thermal element 140 moves to the left into engagement with its left hand contact in response to an increase in 55 temperature that a circuit is closed across con-

ductors 137 and 139 to energize relay winding 136. Simultaneously therewith, a holding circuit for the relay winding is closed by switch 142. Energization of the winding also causes closure of switches 143 and 144, the former closing an energizing circuit to the solenoid controlling the operation of valve 73 in the refrigerant circulating system. This circuit leads from one side of the source of power through conductors 133 and 145 to switch 143, conductor 146 to relay 147 and back through conductor 148 to the other side of the source. Closure of switch 144 establishes a circuit through conductor 149 to a relay 150 controlling the operation of a switch 151 adapted in turn to energize compressor motor 69 by connecting the latter to the source of supply through conductors 152.

During that portion of the day that transformer 135 is energized, the auxiliary cooling means is made effective to cool air flowing through the conditioner associated with zone 12 and the control thereof is likewise transferred to a thermostat located in room F. This thermostat, indicated by reference numeral 153, has its thermal responsive element 154 and associated contacts connected through conductors 155 and 156, 157 to the secondary of transformer 135 and to relay winding 158. When the thermal element 154 moves to the left into engagement with its left hand contact in response to an increase in temperature 3 a circuit is closed across conductors 155 and 156 to energize relay winding 158. Energization of the relay effects closure of a holding circuit for the relay by means of switch 159. Simultaneously, switches 160 and 161 are closed, the former energizing 3 through conductor 162 a solenoid 163 controlling the operation of valve 76 in the refrigerant line leading to evaporator 59. Switch 161 closes a previously described circuit through conductor 149 to energize relay 150 and to initiate operation 4 of compressor motor 69.

Heating of the air is, as has been previously brought out, under the control of co-operating but independent thermal responsive means. Each zone is provided with a thermostat located in 4 the rooms C and F, respectively, having average heat gains and losses controlling the admission of a heating medium to the heating coil associated with the conditioner of a particular zone. A thermostat 164 positioned in room C has its thermal element 165 and associated contacts connected by means of conductors 166, 167 and 168 to a relay comprising a transformer 169 and relay winding 170 similar to those already described. The primary of the transformer receives energy 5 from a suitable source 89 to which it is directly connected. The thermal element 165 is so arranged that it moves to the left in response to a decrease in temperature, and it may be noted from the drawing that when it engages its left hand contact a circuit is closed across conductors 167 and 168 to energize relay winding 170. Energization of this winding effects closure of 6 switches 171, 172, and 173 and opening of switch 174. The closure of switch 171 establishes a holding circuit for relay 170 that maintains the relay energized until such time that a short circuit is formed across relay winding 170 through the connection of conductors 166 and 167 by thermal element 165 in response to an increase 7 in temperature.

Closure of switch 172 causes a reversal in the action of thermostats 25 and 26 associated with the dampers controlling the admission of fluid to each zone. It is evident that if a single thermostat is to be used in each room that it cannot 75

be used for control of the same dampers both in winter and in summer unless some reversing means are provided. The reversing arrangement to be described more fully when damper actuating means 29 is described provides a simple and efficient means for reversing the connections between the room thermostats and the damper actuating means.

The opening of switch 174 and closure of 173 effects operation of the two position motor operated valve 43 governing the admission of steam to heater coil 42. The switch 174 is connected to the motor of valve 43 by conductor 175 and switch 173 is connected thereto by conductor 176. A connection 177 from the source of supply also leads to the valve operating motor and it will be obvious to those skilled in the art that if the motor is of the well known type having a double winding, energization of a portion of which operates it in one direction and energization of the remaining portion operates it in another direction, then the alternate breaking and making of the circuits defined by conductors 175 and 176 will result in operating the steam control valve alternately into its open and closed positions.

The admission of steam to heater coil 56 of conditioner 18 is governed in a similar manner by a thermostat 180 in room F. The thermal element 181 and associated contacts are connected by means of conductors 182, 183, and 184 to a transformer 185 and relay winding 186. The transformer is connected directly to the source of supply 89. When the thermal element 181 moves to the left in response to a decrease in temperature it closes an energizing circuit for winding 186 across conductors 183 and 184. Winding 186 thereupon establishes a holding circuit for itself by closure of switch 187.

The action of room thermostats 27 and 28 controlling the dampers governing the admission of heat exchange medium to the various rooms in zone 12 is reversed by closure of switch 188. The resulting establishment of a circuit from one side of power supply 89 on the right hand side of the figure through conductor 189 to damper actuating means 31 and 32 and from thence to the other side of the power supply line 89 at the left hand side of the drawing is in a manner that will be more fully described when the damper actuating means 29 is described in detail. Energization of relay 186 also causes closure of switch 190 and opening of switch 191 controlling circuits 192 and 193 leading to the operating means associated with valve 57 controlling the flow of steam to heater coils 56 of conditioner 18. The middle wire 178 of operating member 57 is connected to the middle wire of operating member 43 and from thence to the source of power through connection 177.

The individual damper controlling thermostats 25 to 28, inclusive, and the associated damper actuating mechanisms 29 to 32, inclusive, are all alike and consequently, I have shown in detail only the one for room A. The power is supplied from the source 89 through transformers 194 and 195 to relay winding 196 and damper operating motor 197, respectively, the transformers being connected to the power supply line by conductors 198. One terminal of winding 196 is directly connected to the thermal element of thermostat 25 through conductor 199 and the other side thereof is connected to a switch member 200 movable from engagement with a lower contact, connected to the right hand stationary contact

of thermostat 25 through a conductor 201, into engagement with an upper contact connected to the left hand stationary contact of thermostat 25 through a conductor 202. Associated with switch 200 is a second switch 203 similarly movable from a lower contact into engagement with an upper contact. The opposite contacts associated with these two switches are interconnected in such manner that as the switches 200 and 203 are moved upward by energization of a reversing relay 204 the action of the thermostat 25 with respect to the relay 196 is reversed.

The reversing relay 204 is under control of the thermostat 164 in room C, the latter controlling the energization of relay winding 170 15 which, when energized, effects closure of switch 172. Closure of this switch energizes the reversing relay 204 through a conductor 205. Associated with relay 196 is a switch 206, the closure of which establishes the holding circuit for 20 relay 196.

Also associated with relay winding 196 is a second switch 207 controlling the energization of motor 197 to open and close the damper. Also associated with the switch are a pair of co-operating contacts termed, for sake of simplicity, upper and lower contacts, and a limit switch mechanism comprising a cam 208 and movable switch members 209 and 210. Engagement of switch member 207 with its associated upper contact upon energization of relay winding 196 completes a circuit from that contact through conductor 211, motor 197, secondary winding of transformer 195, conductors 212 and 213, limit switch 210 and conductor 214 to switch member 207. Motor 197 thereupon operates to open damper 33 by means of crank arm 215 while at the same time cam 208 is rotated. At the time damper 33 is in its fully open position the cam 208 is rotated 180° to open limit switch 210 and close limit switch 209, thereby de-energizing motor 197. Upon subsequent movement of switch member 207 from its associated upper to lower contact upon de-energization of winding 196 a circuit is established from the lower contact 30 through conductors 213 and 212, secondary winding of transformer 195, motor 197, conductor 211, limit switch 209, and conductor 214 to switch member 207, thereby energizing motor 197 to return damper 33 to its closed position. Cam 50 208 rotates 180°, opening limit switch 209 to de-energize motor 197 and closing limit switch 210 preparatory to the next energization of relay 196.

It will be understood that other well-known forms of damper actuating means may be employed if desired. This is true particularly if modulated control of the damper is desired and if such modulated control is deemed to be desirable, the damper operating motor and control above described may be modified in the manner shown in Letters Patent 1,902,327—Hall, also assigned to the assignee of the present application.

The remaining damper actuating mechanisms and controls are similar in all respects to that just described. Similar connections have been labeled similarly in all cases, with the exception of the conductor leading to the reversing relay associated with the thermostats in zone 12. As stated previously, this conductor is labeled with 60 reference numeral 189 and leads directly to a switch 188 that is operated by relay 186.

Before proceeding with the description of the operation of the system as a whole, it will be necessary to assign certain arbitrary values at which

the various thermostats will operate. It will be assumed that the various thermostats 25 to 28, inclusive, controlling the operation of the dampers will be set to operate at 80° in summer and 72° in winter. No automatic means for so changing the setting of these thermostats is shown and as far as the apparatus is concerned the shift may be made manually whenever desired. Thermostats 164 and 180 are set to operate at 72° during the day time and may be set to operate at 60° during the night time, provided a corresponding change is made in the setting of the various room thermostats. The day and night control has not been disclosed in the drawing but since these devices are well known to those skilled in the art they may be readily applied, if desired. The thermostats controlling the cooling system are arranged to operate at slightly different temperatures in order to equalize the length of time the main and auxiliary compressor motors will be in operation. The thermostats controlling the main system are set to operate at a temperature which will be assumed to be 80° and the thermostats controlling the operation of the auxiliary cooling apparatus that is shifted from one conditioner to the other is set to operate at 78°.

The operation as it occurs during the summer when cooling is required is first described. The telechron motors 124 driving time switches 122 and 123 will be energized constantly. Consequently, these switches will be operated in a manner described above to energize the main cooling apparatus associated with the conditioners through operation of switch 122 and relay 129 and the auxiliary cooling apparatus will be selectively connected to either conditioner or disconnected entirely as desired under the control of switch 123. It will be assumed that switch 122 is of the type wherein the circuit is closed during 24 hours a day but which is provided with means whereby certain days may be skipped entirely. That is, on certain days when cooling is not required, the apparatus may be de-energized. On the other hand, switch 123, as has been described above, is of the type whereby a contact is made from the middle pole of the mercury switch 126 to the contacts at opposite ends only during certain periods of the day. For purpose of illustration, it will be assumed that contact is made between the middle and right hand poles during the forenoon; that is from 6 a. m. to 12 m., and from the middle pole to the left hand pole from 12 m. to some time such as 8 p. m.

With these assumptions in mind, it may be noted that a circuit will be closed by means of switch 122 to energize relay 129 by connecting the latter across supply line 89 through conductors 121 and 127, mercury switch 125 and conductor 128. Assuming the time of day to be before 6 a. m., then switch 123 is in its open position and the auxiliary cooling apparatus inoperative. Energization of relay 129 will cause upward movement of its associated armature and closure of switch 92. This effects energization of primary winding of transformer 87, connecting it directly across the supply lines through conductors 90 and 91. After a brief interval, as determined by time delay means 112 associated with switch 111, a similar circuit will be closed by that switch to energize primary winding of transformer 107.

Whether or not motors 67 and 53 will be energized by the closure of these relays will in turn depend on the position of the thermostats 81 and 101 in zones 11 and 12, respectively. If these

thermostats are in their closed position because temperatures higher than 80° obtain, then relays 88 and 108 associated therewith will be promptly energized with the resulting closure of switches 94 and 114. The closure of these switches will energize relays 95 and 115 controlling the energization of compressor motors 53 and 67. However, if the temperature within zones 11 and 12 is below 80°, the thermostats 81 and 101 would not be in their closed position and, consequently, the respective motors would not be energized and the only result of the energization of relay 129 would be the energization of the primary windings of the above mentioned transformers. If the temperature within zone 12 rises to a value greater than 80°, then thermostat 101 will close the energizing circuit for relay 108 and the energization of the latter will effect the closure of switches 113 and 114. Closure of the former energizes the holding circuit for the relay and closure of the latter closes a circuit through conductors 116 and 117 for relay 115, the latter effecting closure of switch 119 and consequent energization of motor 67. Thereupon the cooling apparatus associated with zone 12 is set into operation and as the air flows by evaporator 58 it is cooled and distributed to the various rooms through central duct 19.

Since the damper controlling thermostats 27 and 28 in zone 12 were assumed to operate at 80°, these thermostats will close an energizing circuit for their relay windings 196 and cause operation of their associated dampers 35 and 36 to open positions in a manner that has been described previously. It may be noted further that if some particular room is below a temperature of 80° then the thermostat positioned in that room will remain in such position that the damper associated with that room will be maintained in its closed position. In this manner cooling medium is distributed only to those of the rooms subject to unusual conditions and which require it.

When the average temperature within the zone decreases to a temperature below 80°, as indicated by thermostat 101 in zone 12, then thermostatic element 102 moves to its right hand position and short circuits relay 108. This results in the de-energization of the relay and motor 67 until such time as the temperature within zone 12 again reaches a value above 80°. The operation of the cooling means associated with conditioner 13 for zone 11 is the same in all respects and will not be further described.

After six o'clock in the morning, or any other desired time, time switch 123 closes a circuit between the middle and right hand poles of mercury switch 126 to place the auxiliary cooling apparatus into condition to operate. Thereupon an energizing circuit for the primary of transformer 132 is closed in a manner previously described. Assuming first that the temperature within zone 11 is below a value necessary to cause operation of thermostat 141 to its closed position, thereupon the only effect of the closure of switch 126 is the energization of transformer 132. If the temperature within zone 11 thereafter increases to a value above 78°, an energizing circuit is closed for relay 136 through conductors 137 and 139. Energization of the relay effects closure of switches 142, 143, and 144. Closure of the first establishes a holding circuit for the relay. Closure of the second closes the energizing circuit for relay 147 through conductors 133 and 145, switch 143, conductor 146, relay 147 and con-

ductor 148. Thereupon valve 73 is operated to its open position to permit the flow of refrigerant to auxiliary evaporator 45 associated with conditioner 13. Closure of switch 144 closes an energizing circuit for relay 150 controlling the energization of compressor motor 69 associated with the auxiliary cooling apparatus. Thus, it will be seen that the auxiliary system will be placed into operation to further cool the air in zone 11 during 10 that period of the day when an increased capacity is required to properly cool that part of the building. In addition, it will be noted that the auxiliary apparatus is placed into operation at a somewhat earlier time than the main cooling apparatus for zone 12 because of the fact that it is set 15 into operation at a somewhat lower temperature. The reason for this is that the main cooling apparatus is in operation at certain times for a greater part of each twenty-four hours, whereas 20 the auxiliary apparatus is in operation at most for about 12 to 14 hours and, consequently, it is desirable that the auxiliary apparatus be utilized over a comparatively longer period of the total time that it is in operation so as to operate the 25 various units for more equal lengths of time.

Both the main and auxiliary cooling units will be effective to supply the cooling necessary for zone 11 from 6 a. m. to 12 m. and only the main unit will supply zone 12. However, after noon 30 the time switch 123 will be actuated in such manner as to open the first closed circuit and close the circuit across the middle and left hand poles of 126. As a result, transformer 132 is de-energized and transformer 135 energized; 35 switches 142, 143, and 144 opened; and switches 159, 160 and 161 closed. If thermostat 153 associated with this system is in a position calling for cooling, it will be noted that, since this system is similar to that just described, it will operate to 40 open valve 76 allowing the refrigerant to flow to evaporator 59 associated with conditioner 18 and also energize compressor motor 69. The operation is in all respects similar to that described and will not be described at any greater length. 45 Thus it will be seen that the capacity auxiliary apparatus is transferred from one conditioner to the other under the control of time switch 123 and that it will be set into operation at a temperature slightly lower than that at which the 50 main cooling apparatus associated with each zone will be set into operation.

Thus far, nothing has been said about the operation of the heating apparatus but, because of the fact that the thermostats controlling the operation of the latter are not operated into a circuit closing position until a temperature of 72° or less has been reached, the relays associated therewith will remain de-energized. If weather conditions change to such an extent that the 55 temperature surrounding the various thermostats decreases to a value less than 72°, then the cooling apparatus is inoperative because of the fact that the temperature is below the values, namely, 78° and 80°, at which these thermostats are set to 60 render their associated cooling apparatus inoperative.

Assuming that the temperature falls below 72°, then thermostats 164 and 180 will move to the left to energize their respective relays 170 and 70 186 in the manner heretofore described. Closure of these relays establishes a holding circuit for each through closure of switches 171 and 181. Simultaneously, closure of switches 172 and 188 establishes energizing circuits for the reversing 75 relays 204 associated with each of the various

room thermostats, each relay in turn actuating its associated switches 200 and 203 from contact with their lower contacts into engagement with their upper contacts to thereby reverse, with respect to temperature, the effect of the room thermostats on the damper actuating control system. Therefore, the room thermostats will now operate to open the dampers on a decrease in temperature below a value of 72° and the closure of the same when the temperature is above this value. 10

Energization of relays 170 and 186 also results in the operation of the valves controlling the flow of steam to the heating coils of the conditioners. The relays actuate switches 173 and 190 to their closed position and simultaneously open switches 174 and 191, thereby causing the valve motors to operate the valves to their open positions. Consequently, the air passing through the conditioner is now heated and distributed through ducts 14 and 19 to the zones. If the temperature within 20 any of rooms A, B, D, or E falls below a value of 72° the thermostat therein will close a circuit for its associated relay 196 energizing motor 197 to operate the latter through 180° in a manner previously described. Alternate energization and 25 de-energization of relay 196 will therefore operate to open and close the damper associated with the particular room. When the average temperature within the zones as indicated by thermostats 164 and 180 in rooms C and F increases to a value above 72° the thermostats will 30 move to positions wherein relays 170 and 186 are short circuited, causing deenergization of these relays and of reversing relays 204 as well. Additionally, the switches 173 and 190 are opened 35 and switches 174 and 191 closed to operate the motors of valves 43 and 57 to their opposite or closed positions to discontinue the flow of steam to the heater coils.

It may be desirable in certain types of systems to provide means whereby the temperature maintained within the building is kept at a lower value during the night than during the day as by providing thermostats therein with a day-night control. Such a system may be applied in connection with the thermostats 164 and 180 and the various room thermostats. If applied, it will be 40 obvious to those skilled in the art that my system will operate to maintain lower temperatures whenever desired and as controlled by timing means associated with the thermostats. 45

As stated previously, it often occurs that in large buildings the requirements of the various tenants are likely to be different. One such difference arises in systems of this type where one 50 tenant requires a continual circulation of air through the portion of the building that he occupies. It is obvious that with but a single duct leading to each room and a damper operable from a closed to open position and vice versa 55 continual circulation cannot be obtained. Therefore, I have provided a means whereby any space or spaces may be provided with continual circulation of air. The damper 37 in duct 24 leading to room B is interlinked with damper 34 in duct 14 60 in such manner that one damper will be in its open position and the other in its closed position and that the room will be supplied with either conditioned air or with a combination of fresh and recirculated air. 65

It will be obvious to those skilled in the art that my invention is not limited to the system described above. It may be used in conditioning any number of zones, some of which may be provided with independent conditioners after the 70

- manner of the conditioners described but which are provided with only a single cooling surface. Furthermore, it is not essential that the auxiliary cooling means be effective at the times stated.
- 5 It may be convenient to make them effective for but two hours in the morning and a like period in the afternoon and this change could be made by merely changing the operation of time switch 123 in an obvious fashion.
- 10 In other cases it may be convenient to divide the building into more than two zones and sequentially to shift the capacity of the auxiliary cooling equipment to the various zones to compensate for the effect of the sun's rays.
- 15 What I claim as new and desire to secure by Letters Patent of the United States is:
1. In an air conditioning system, the combination including a plurality of spaces to be conditioned, an air conditioner comprising air circulating and conditioning means, a central duct leading therefrom, individual branch ducts leading from the latter to each of said spaces, a central return duct and branch ducts leading from each space to said return duct, means for regulating the flow of said conditioned air to predetermined spaces through said branch ducts, thermal responsive means in each of said predetermined spaces for controlling said last mentioned means, a duct leading from a point between the 20 air circulating and conditioning means to one of said predetermined spaces and by-passing said conditioner, and means for regulating the flow of by-passed air through said last mentioned duct, said last mentioned means being operatively associated with the regulating means controlling the flow of conditioned air through a branch duct to said one of said predetermined spaces and adapted to close said by-pass duct when the branch duct is open, and vice versa, and controlled by the thermal responsive means controlling the flow of conditioned air to said spaces whereby said space is continuously supplied with conditioned or by-passed air.
  2. In an air conditioning system, a plurality of spaces to be conditioned, means including a conditioner and a central duct system with associated branch ducts for supplying said spaces with conditioned medium, means including thermal control devices located in said spaces for regulating the flow of medium through said branch ducts to said spaces, an independent duct leading from the conditioner to a predetermined one of said spaces for supplying unconditioned air thereto, and additional means controlled by the thermal control device in said predetermined space for regulating the flow of medium through said independent duct, said flow regulating means comprising interconnected dampers in said branch and independent ducts so arranged that when one damper closes its respective duct the other opens its associated duct, whereby said space is supplied continuously with either conditioned or unconditioned air.
  3. In a temperature control system, the combination including a thermostat responsive to variations in a predetermined temperature condition, means controlled by said thermostat for varying the temperature of a heat exchange medium upon variation in said temperature condition to a predetermined value, means for supplying said medium to a space including reversible means for increasing and decreasing the supply of said heat exchange medium to said space, a separately operable thermostat responsive to variations in the temperature of said space for

reversing said regulating means to vary the supply of heat exchange medium to the space in accordance with variations of the temperature in the space from a predetermined value, and means operable under the control of said first thermostat for reversing with respect to the temperature variations in said space the reversing control of said second thermostat on said reversible means.

4. In a heating and cooling temperature control system, the combination of reversible regulating means operable in each direction for oppositely controlling temperature under heating and cooling conditions, means for reversing said regulating means, and means including a pair of thermal responsive devices each having a control element reversely operable between two control positions upon temperature variations in opposite directions between limits, said pair of thermal responsive devices being relatively adjustable for effecting the reverse operations of the control element of one of said devices at temperature limits below the lower temperature limit of the other device under heating conditions and above the upper temperature limit of the other device under cooling conditions, and concatenated reversing connections between said elements for jointly controlling the operation of said reversing means whereby said regulating means will be selectively actuated in each direction in response to temperature variations in opposite directions upon said relative adjustment of said devices.

5. In a temperature control system the combination of a reversible temperature regulating device, a reversible electric motor for operating said device, means for selectively controlling the operation of said motor including a pair of thermal responsive means, each having a thermostatic control element responsive to a different one of two predetermined temperature conditions and separately adjustable for response at different temperature values and each having a circuit controlling element controlled by the corresponding thermostatic element for operation in opposite directions between two circuit closing positions in response to opposite variations in temperature from the value to which the corresponding thermostatic element is adjusted to respond, and concatenated circuit reversing connections between said circuit controlling elements for effecting operation of said motor in predetermined opposite directions upon operation of one of said circuit controlling elements between the two circuit closing positions thereof with the other of said circuit controlling elements in one of the two circuit closing positions thereof and for effecting operation of said motor in the reversed opposite directions upon the same operation of said one circuit controlling element with said other circuit controlling element in the other of the two circuit closing positions thereof.

6. In a zone temperature control system, the combination of a pair of thermostats, one being responsive to the temperature of one space in the zone and the other being responsive to the temperature of another space in the zone, heat exchange means controlled by said one thermostat for varying the temperature of all the spaces in the zone, temperature regulating means for modifying the action of said heat exchange means and separately operable under the control of said other thermostat for varying the temperature of said other space with respect to the temperature of said one space, and means operable under the control of said one thermostat upon a predetermined change in the temperature of said one

space for reversing the temperature regulating operation of said regulating means under the control of said other thermostat.

7. In a multiple temperature regulating system the combination including a plurality of thermal responsive devices, one of said devices being responsive to a predetermined one of a plurality of jointly variable temperature conditions, and each of the other of said thermal responsive devices being responsive to a corresponding one of said temperature conditions, temperature changing means controlled by said one device for jointly varying said temperature conditions, separate temperature regulating means for modifying the action of said temperature changing means and controlled by each other of said thermal responsive devices for separately regulating the corresponding temperature condition, and means controlled by said one temperature responsive device for reversing the control of all said other temperature responsive devices over the temperature regulating means controlled thereby upon a predetermined control of said temperature changing means.

8. In a multiple temperature control system for a plurality of spaces having related ambient temperature conditions, the combination of means for supplying heat exchange medium to all said spaces, means for heating said medium, separately operable means for cooling said medium, means including thermal responsive means responsive to the temperature in one of said spaces for starting operation of said cooling means when the temperature in said one space exceeds a predetermined maximum value and for starting operation of said heating means when the temperature in said one space decreases below a predetermined minimum value, a separate thermostat in each of the remainder of said spaces having separate means controlled thereby for regulating the flow of said medium to the corresponding space, and means under the control of said first mentioned thermal responsive means for effecting operation of all said separate thermostat regulating means to increase the flow of medium to the corresponding space when the heating means is in operation and the temperature in said space decreases below a predetermined value and to increase the flow of medium to the corresponding space when said cooling means is in operation and the temperature in said space increases above a predetermined value.

9. In a multiple zone cooling system, the combination of a pair of zones normally having maximum heat gains during different predetermined periods, separately operable cooling means for each of said zones, separate auxiliary heat absorbing means for each of said zones having a common operating element, thermal responsive means in each zone for rendering said common operating element and the corresponding auxiliary heat absorbing means effective to cool the corresponding zone upon a predetermined temperature variation in the corresponding zone, and time controlled means for rendering the thermal responsive means of one zone effective during the period of maximum heat gain of said zone, and the thermal responsive means of the other zone effective during the period of maximum heat gain of the other zone.

10. In a variable demand cooling system the combination of a pair of zones normally having maximum cooling demands during different predetermined periods, separate cooling apparatus for each zone comprising an air condi-

tioner having means for circulating air from said conditioner to the corresponding zone, and refrigerating apparatus for cooling the air, an auxiliary refrigerating apparatus having separate heat absorbing means for cooling the air in each of said conditioners, and time control means for oppositely controlling the separate heat absorbing means of said auxiliary apparatus to increase the air cooling capacity of one of said conditioners and decrease the air cooling capacity of the other of said conditioners during each of said predetermined periods.

11. In a multiple zone cooling system, the combination of a pair of zones normally having maximum heat gains at different predetermined times, separate air conditioners for each zone, each having a main and an auxiliary air cooling means therein, main and auxiliary thermal responsive means in each zone for selectively rendering the main and auxiliary cooling means of the corresponding conditioner effective and ineffective, and time controlled means synchronized with the variations in heat gain of said zones for selectively rendering a corresponding one of said auxiliary thermal responsive means effective at said different predetermined times.

12. In a multiple zone cooling system, the combination of a plurality of zones normally having maximum heat gains during different time periods, a separately operable main cooling means for each zone, thermostatic means in each zone for controlling operation of the corresponding main cooling means in accordance with predetermined temperature variations therein, a separately operable auxiliary cooling means having a separately operable cooling element for each zone, and a timing control device having a thermostatic means in each zone selectively controlled thereby for rendering the corresponding cooling element operable and effecting operation of said auxiliary cooling means during the period of maximum heat gain of the corresponding zone in accordance with predetermined temperature variations therein.

13. In a multiple zone cooling system, the combination of a plurality of zones normally having maximum heat gains during different time periods, a separate air conditioner for each zone, each having a main cooling means and a thermostatic control means therefor responsive to predetermined variations in temperature of the corresponding zone, auxiliary cooling means having a separate cooling element in each conditioner and a common operating element, valve means for selectively connecting said cooling elements with said operating element, and means including a timing control means and a separate thermostatic means in each zone selectively controlled by said timing control means for effecting operation of said auxiliary cooling means and said selective valve means during the period of maximum heat gain of the corresponding zone in accordance with predetermined temperature variations therein.

14. In a multiple zone cooling system, the combination of a plurality of zones normally having maximum heat gains during different time periods, a separate air conditioner for each zone, each having an air circulating means and a main air cooling means provided with thermostatic control means for effecting operation of said main cooling means in accordance with predetermined temperature variations in the corresponding zone, auxiliary cooling means having a separate cooling element in each air conditioner

and a common operating element therefor, each of said cooling elements having a separately operable valve for operatively connecting the element with said operating element, and means including a timing control means and a thermostatic means in each zone selectively controlled thereby for selectively controlling said valve means and selectively effecting operation of said operating element during the period of maximum heat gain of the corresponding zone and in accordance with predetermined temperature variations therein.

15. In an air conditioning system for a plurality of spaces, the combination including a central air conditioner having means for circulating air to all said spaces, means for heating the circulated air and separately operable means for cooling the circulated air, thermal responsive means in one of said spaces for selectively operating said heating and cooling means upon variation of the temperature therein below and above predetermined limits, means including a separate thermostat in each of the remainder of said spaces for regulating the flow of conditioned air to the corresponding space, and means controlled by said first mentioned thermal responsive means for reversing with respect to temperature the regulating action of all said separate thermostats upon the selective operation 30 of a predetermined one of said heating and cooling means.

16. In a reversible heat exchange system, the combination of complementary heat exchange means separately operable for oppositely varying the temperature differential of a circulating heat exchange medium, means including a valve movable between limits for varying the flow of said medium, reversible actuating means for moving said valve between said limits, thermal responsive means for reversing said reversible actuating means under opposite heat exchange conditions, independent thermal responsive means for selectively initiating and terminating operation of said heat exchange means, and means under the control of said independent thermal responsive means for reversing with respect to temperature variations the reversing control action of said first mentioned thermal responsive means on said reversible actuating means upon initiation and termination of the operation of a predetermined one of said heat exchange means.

17. In an air conditioning system, the combination of continuously operable means for circulating air to a plurality of spaces, complementary heat exchange means separately operable for oppositely varying the temperature differential of the circulated air, thermal responsive means in one of said spaces for selectively initiating and terminating operation of said heat exchange

means to regulate the temperature of said one space, means including a thermal responsive device in another of said spaces and reversible valve means having reversible control connections with said thermal responsive device for regulating the flow of circulated air to said other space to regulate the temperature of said other space, and means for reversing said control connections upon initiation and termination of operation of a predetermined one of said heat exchange means. 10

18. In combination, complementary heat exchange means separately operable for oppositely varying the temperature differential of a heat exchange medium, means including a valve movable between limits for varying the flow of said medium to regulate a variable temperature condition, reversible actuating means for moving said valve between said limits, means including a temperature responsive device responsive to variations in said variable temperature condition and adjustable for reversing said reversible actuating means at the minimum and maximum limits of two separated temperature ranges, and cooperating temperature responsive means for selectively initiating and terminating operation of said heat exchange means when said predetermined temperature condition varies from a predetermined temperature value intermediate said temperature ranges, and reversing means interconnected between said temperature responsive device and said reversible actuating means for automatically reversing the reversing control of said temperature responsive device over said reversible actuating means upon the initiation and termination of operation of a predetermined one of 30 said heat exchange means.

19. In a reversible heat exchange system, the combination of complementary heat exchange means separately operable for oppositely varying the temperature differential of a circulating heat exchange medium to regulate a variable temperature condition, thermal responsive means responsive to said condition for selectively controlling operation of said heat exchange means, valve means movable between limits for varying the flow of said medium to regulate a different temperature condition, reversible actuating means for moving said valve means between said limits, thermal responsive means responsive to variations in said different temperature conditions for controlling said reversible actuating means, and means under the control of said first thermal responsive means for reversing with respect to temperature the action of said second mentioned thermal responsive means on said reversible actuating means upon predetermined selective operation of said heat exchange means.

EDWARD A. BAILEY.
